FIG. 1 is a perspective view of a vibrational wavelength resonance enclosure showing my new design, the opposite side is a mirror image;

FIG. 2 is a bottom perspective view thereof, the opposite side is a mirror image;

FIG. 3 is an inside top elevational plan view thereof, the undisclosed portions are not part of the claimed design;

FIG. 4 is a bottom inside elevational plan view thereof, the undisclosed portions are not part of the claimed design;

FIG. 5 is a second embodiment of a vibrational wavelength resonance enclosure showing my new design, the undisclosed portions are not part of the claimed design; and,

FIG. 6 is a bottom inside elevational view thereof.
